KNIFE SHARPENER

BY *W.B. Harman*
ATTORNEY

UNITED STATES PATENT OFFICE

2,542,472

KNIFE SHARPENER

Glenn A. Brinkley, Youngstown, Ohio

Application March 6, 1950, Serial No. 147,954

2 Claims. (Cl. 76—86)

1

This invention relates to a knife sharpener and more particularly to a knife sharpener incorporating sections of half-round files.

The principal object of the invention is the provision of a knife sharpener incorporating sections of half-round files against which a knife may be drawn for forming a hollow ground edge thereon.

A further object of the invention is the provision of a knife sharpener having opposed pairs of sections of half-round files separated by guide means forming right and left pass areas for a knife to be sharpened.

A still further object of the invention is the provision of a simply and inexpensively formed knife sharpener which will form hollow ground edges on a knife moved longitudinally therethrough.

The knife sharpener disclosed herein comprises a simple and efficient solution of the problem of sharpening knife blades and particularly in forming an even longitudinally straight and hollow ground sharpened edge which is the ideal formation of a knife edge. It has heretofore been proposed to utilize various assemblies of discs, abrasive wheels and the like against which relatively small areas of the knife blade are sharpened. Such sharpening means form a longitudinally irregular pattern in the edge of the knife and invariably form an angular edge rather than a hollow ground edge as preferred.

The present invention utilizes opposed sections of half-round files spaced by appropriate guiding means so that a knife blade positioned longitudinally of one of the files and adjacent the guiding means and drawn therealong will automatically be presented to the file in such a manner that a longitudinally straight hollow ground edge is formed on one side of the knife blade. The knife, upon being moved to the other side of the guide means and drawn through the sharpener, again engages its opposite side on the other of the two sections of half-round files and thereby both edges of the knife may be sharpened.

With the foregoing and other objects in view which will appear as the description proceeds, the invention resides in the combination and arrangement of parts and in the details of construction hereinafter claimed, it being understood that changes in the precise embodiment of the invention herein disclosed can be made within the scope of what is claimed without departing from the spirit of the invention.

The invention is illustrated in the accompanying drawing, wherein:

2

Figure 1 is a perspective view of the knife sharpener showing a knife blade positioned therein.

Figure 2 is a side elevation of the knife sharpener shown in Figure 1.

Figure 3 is a plan view of a metal section used in forming a portion of the knife sharpener shown in Figures 1 and 2.

Figure 4 is a perspective view of the completed metal section formed from the blank shown in Figure 3.

By referring now to Figures 1 and 2 of the drawings it will be seen that the knife sharpener comprises a base 10 having upturned side flanges 11 and 12. Openings 13 in the base 10 are provided so that it may be fastened to a supporting surface if desired. Two pairs of oppositely disposed openings are formed in the side flanges 11 and 12 and rivets 14 and 15 are positioned therethrough to pivotally secure the lower ends of a pair of vertical body members 16 and 17 to the base 10. The body members 16 and 17 have rolled upper and lowermost edges 16A and B and 17A and B, respectively, the rolled edges 16B and 17B being formed about the rivets 14 and 15 and the upper rolled edges 16A and 17A being formed about a pair of bolts 18 and 19 which are also used to secure U-shaped members 20 and 21 to the body members 16 and 17 and in pivotal relation thereto. The U-shaped members 20 and 21 are pivoted to the bolts 18 and 19 approximately midway between the ends of the arms of the U-shaped members 20 and 21 so that the free ends of the arms project beyond the pivots formed by the bolts 18 and 19 and form manually engageable handles 20A and 20B and 21A and 21B.

The interconnecting sections of the U-shaped body members 20 and 21 are oppositely disposed with respect to one another and extend transversely of the base 10 and present flat surfaces to which are secured two sections of half-round files 22 and 23, respectively. These half-round sections of files have a cut surface on their half-round side of approximately 46 teeth per inch with the flat sides being unbroken.

The half-round files 22 and 23 are affixed to the flat transversely positioned, opposed, vertical surfaces of the U-shaped body members 20 and 21 as best shown in Figure 2 of the drawings, it being observed that the center of the radius defining the half-round of each of the files 22 and 23 is spaced with respect to the centers of the bolts 18 and 19 so that when the U-shaped body members 20 and 21 are moved, as shown in Figure 2

of the drawings, the half-round surfaces of the files 22 and 23 engage a guide member 24 at different vertical planes thereon and thereby present a different wearing surface to a knife blade to be sharpened thereagainst. For example, in Figure 2 of the drawings the half-round file 22 is engaging the guide 24 at a point on a horizontal plane with the center of the bolt 18, while the half-round file 23 is engaging the guide 24 on its opposite side at a point slightly therebelow due to the tilting or pivoting of the U-shaped body member 21 on the bolt 19. It will thus be seen that as the files wear from use they may be moved as described to present new wearing surfaces still at the same angle of tangency to a knife blade to be sharpened.

The guide 24 is corrugated vertically as seen in Figures 1 and 4 of the drawings and it will be seen to be formed of a blank 25 shown in Figure 3 of the drawings including the leg sections 25A and foot sections 25B. The blank 25 is corrugated to form the guide 24 as shown in Figure 4 of the drawings and also in the assembly of the knife sharpener in Figures 1 and 2 of the drawings. The corrugations permit the filings to drop away from the sharpening area.

It will be obvious to those skilled in the art that the guide 24 spaces the files 22 and 23 with respect to one another but more importantly forms a vertical guide against which a knife, shown in Figure 1 and indicated by the letter K, may be positioned and held while the same is moved transversely of the device as shown by the arrow in Figure 1 of the drawings. In such position the one side of the knife will engage against the rounded edges of the corrugations of the guide 24 while the other side thereof and particularly the lower edge thereof which is the cutting edge will engage against the half-round file 22 and as it is drawn transversely of the device and longitudinally of the half-round file 22 will cause a hollow ground, longitudinally straight, sharpened edge to be formed on that side of the knife blade. The other side of the knife blade is then sharpened by positioning the knife on the opposite side of the guide 24, the right side as shown in Figures 1 and 2 of the drawings. Alternate strokes of the knife through the knife sharpener will thus straighten and sharpen both sides of the knife blade to the end that a perfectly sharpened knife results.

Modifications in the construction disclosed will occur to those skilled in the art. For example, the half-round file sections 22 and 23 may be cemented to the U-shaped body members 20 and 21 or they may be clamped thereto or otherwise affixed thereto in any manner known in the art. The guide 24 may also be formed of a plurality of vertically standing round wire sections, if de-

sired, and in either event it will occur to those skilled in the art that the cuttings from the knife blade will be able to fall downwardly onto the base 10, as in the case of the corrugated guide 24 the spaced vertically standing rounded sections engage the knife blade and provide adequate passageway for such cuttings between the same.

Still referring to Figures 1 and 2 of the drawings it will be seen that means for holding the files 22 and 23 in desirable engagement with the guide 24 is shown and comprises a bolt 26 having a butterfly nut 27 engaged thereon and passed through appropriately formed openings in the body members 16 and 17.

Still referring to Figure 2 of the drawings it will be seen that the guide 24 and particularly the foot 25B thereof is secured to the base 10 as by rivets 28 so that the entire device forms a unitary structure capable of simple fabrication and economic assembly.

It will thus be seen that the knife sharpener disclosed herein meets the several objects of the invention.

Having thus described my invention, what I claim is:

1. A knife sharpener comprising a base having upstanding side flanges, a pair of body members pivoted transversely of the said base and between the said flanges, a guide member positioned midway between the body members and including a plurality of vertically positioned spaced rounded members, secondary body members pivoted to the said body members and sections of half-round files secured to said secondary body members in oppositely disposed relation to one another and spaced by said guide means, and means urging the said body members toward one another to hold the said sections of half-round file in desirable engagement against said guide means.

2. The knife sharpener set forth in claim 1 and further characterized by the formation of the said guide means as a vertically corrugated member positioned on said base and extending above the said secondary body member.
